UNITED STATES PATENT OFFICE.

HANS P. JOHNSON, OF RACINE, WISCONSIN.

RAIL-JOINT.

1,295,324.

Specification of Letters Patent. Patented Feb. 25, 1919.

Application filed November 11, 1918. Serial No. 262,040.

To all whom it may concern:

Be it known that I, HANS P. JOHNSON, a citizen of the United States, residing at Racine, in the county of Racine and State of Wisconsin, have invented certain new and useful Improvements in Rail-Joints, of which the following is a specification.

This invention has reference to improvements in rail joints of that type in which the use of the usual fish plates and bolt and nut connections is wholly dispensed with and in which the meeting ends of the rails are sustained on rail chairs and the rails are held by opposing clamping members and co-operating devices that hold the parts to their assembled position.

My invention primarily has for its purpose to provide an improved rail joint of the general character stated, of a comparatively simple and inexpensive construction, in which the efficiency of the clamping elements is not effected by the changes of temperature, and in which wedging devices are combined with oppositely disposed clamping members, whereby any tendency of the rails to loosen up, under contraction, is practically and positively overcome by automatic shifting of the wedging devices.

Another object of my invention is to provide an improved rail joint having the co-operating parts especially designed for effectively maintaining the meeting ends of the rails in an assembled relation and such meeting ends of the rails so sustained that the pounding action that usually takes place as the rolling stock passes thereover, is reduced to the minimum.

The novel features of my invention will be first described in detail, specifically pointed out in the appended claims and illustrated in the accompanying drawings, in which:

Figure 1 is a perspective view of my improved rail joint, the parts being in the assembled or operative position in connection with the meeting ends of a pair of rails.

Fig. 2 is a transverse section thereof taken on the line 2—2 on Fig. 1.

Fig. 3 is a plan view of the same, parts being in horizontal section.

Fig. 4 is a cross section of the same taken on the line 4—4 on Fig. 1.

Fig. 5 is a perspective view that illustrates the manner in which the combined chair and housing member and the clamping plates are assembled for being slipped onto one end of

one rail section and adjusted for receiving the end of the other rail section, a portion of the latter being indicated in dotted lines.

Fig. 6 shows the manner in which the wedge members and their spring connection are fitted into an operative position, after the parts have been assembled on the rail ends, as indicated in Fig. 5.

Fig. 7 is a perspective view of one of the clamping or joint plates or members herein-after specifically referred to.

In carrying out my invention, I provide a combined rail chair or housing member 1, which includes a base plate 2 that extends the full length of the member 1, as is best shown in Figs. 1, 2 and 3.

Along the upper face, the base plate 2 has a longitudinal groove 3 that extends the full length thereof and into which, when the parts are assembled, fits the base 40 of the rail 4, the outer edges 41 of which base bear against the opposite shoulders or abutments 30 that hold the rail from laterally creeping upon the aforesaid chair base 2.

Along its outer edges, the base plate 2 has spike notches 5 for receiving the spikes 50 that secure the chair onto the cross tie, as shown.

The combined chair and housing member 1 also includes oppositely disposed brace members or webs 6—6 that extend the full length thereof and each of the said brace webs 6—6 has a housing 7 at each end thereof of peculiar construction, as is best shown in Fig. 2, by reference to which it will be seen that the said housings 7 each comprise a longitudinally extended keeper which includes a back bearing 8 that is disposed at an angle of approximately thirty degrees relatively to the web of the rail 4, the purpose of which will presently appear.

The housings 7 are integral parts of their respective brace members 6—6 and the upper edge of one of the said brace members 6 is flush with the tops of the housings 7—7, which latter are at a plane below the tread surface of the rail.

The other brace member 6, midway its length, is formed with a vertical extension 60 whose top surface is flush with the tread face of the meeting ends of the two rail sections.

By projecting the members 6 at one side, as stated, the top surface of the extension 60 constitutes a supplemental tread surface that is engaged by the passing car wheels and

thereby materially overcomes the pounding action that usually occurs at the meeting ends of two rail sections.

By now referring particularly to Figs. 2, 5 3 and 5, it will be seen that the opposite upper and lower walls 80—80 of the housings 7—7 are parallel and are inclined inwardly and downwardly from the back bearing 8 and the said back bearing 8 inclines toward 10 the rail, as is clearly indicated by 82 on Fig. 3.

9—9 designates wedge blocks, one for each housing, and each of the said blocks has a socket 90 on the inner end, the purpose of 15 which will presently appear.

10—10 designate clamp plates, one of which fits each side of the webs of the meeting ends of the rails.

Each clamping plate 10 includes a foot 20 portion 11 and near each end, each of such plates 10 has a wedge-like web 12 provided with an inclined bearing face 13 and the said faces 13 of the webs 12 are adapted for being projected through apertures 63—63 in the 25 corresponding ends of the bracket webs 6 and into the housings 7—7 for coöperating with the wedge blocks 9—9, as is clearly shown in Fig. 2.

In the practical application of my construction of rail joint, the oppositely disposed clamp plates are placed between the web-like braces 6 of the main casting or chair with their bearing portions 12—13 pressed back through their coincident apertures 63—63 in the braces 6—6, so as to give clearance for slipping the chair with the clamp plates over and along the end of one rail section in the direction indicated by the arrow *x* on Fig. 5.

40 When the rail chair with the plates 10—10 has been slid onto the end of one rail section, as stated, the outer or free ends of the clamp plates 10—10 are positioned to afford a clearance for pushing the end of other rail 45 sections (see dotted lines on Fig. 5) to engage with the chair and the clamp plates 10 and for being slid (see arrow *y*) up against the end of the other rail section.

After the rail sections, the chair and the 50 clamp plates have been connected, as stated, the wedge blocks 9—9 are inserted into their respective housings 7—7, it being understood that in fitting the wedges 9—9 into their housings 7—7, they engage with the faces 13 55 of the bearing webs 12 on the clamp plates 10 and, as the said wedges are forced home, they operate to force the plates 10 tightly against the rail web and with their foot portions firmly seated against the base flanges 60 of the rail, such result being provided for by the inclination of the back bearings 8 of the housings and the bearing faces 13 of the plate members 12 (see arrows *z—z* on Fig. 2).

To hold each of the opposing pairs of 65 wedges 9—9 in place and to provide for tak-

ing up tendency of the said wedges to loosen, by reason of wear and contraction of the parts, during low temperatures, I have provided the devices best shown in Figs. 3 and 6, which devices each consist or consists of a 70 pair of telescopically connected rods 15—16, each having, at one end, a disk 15^a—16^a and a stud 15^b—16^b, the latter being provided for seating into the sockets of their respective wedges 9 with which they are connected. 75

17 designates a stout coil spring that is disposed about the telescopic rods 15—16 with the opposite ends thereof abutting the disks 15^a—16^a, as shown.

In fitting the wedge holding devices in 80 place, one rod end is secured in the socket of its respective wedge and by means of a suitable implement the other rod is pushed back (see arrow *b* on Fig. 6) and telescoped into the other rod until the stud 16^b passes the 85 inner face of the adjacent wedge 9, after which the pushed back rod end is shoved laterally until its stud 16^b slips into the socket of the said adjacent wedge 8.

This latter operation completes the practical application of my rail joint, it being understood that, when the wedge holding devices have been applied, as stated and shown, they constitute the means that not only hold the parts positively locked in their 95 proper operative condition but also the means that automatically take up any loosening of the parts by reason of wear or change in temperature.

To prevent tampering and to afford protection against the weather, the spring devices, after being adjusted, are incased by housing plates 18—18 secured by bolts 19—19 or other suitable means.

What I claim is:

1. The combination with the adjacent ends of railway rails; of a chair in which the abutting ends and the base flanges of the rails are disposed, the said chair including oppositely disposed vertical brace members, a clamp plate fitted between each of the said brace members and the web of the opposing rail ends, means engaging the said brace members and the said plates that constantly apply pressure to hold the said clamp members against the web and the base portion of the said abutting rail ends, the said means consisting of wedges that engage the clamp plates, bearings on the brace members with which the wedges engage, the said bearings being vertically inclined with respect to the rails, whereby, when the wedges are forced home, pressure is exerted on the clamp plates to cause them to tightly engage the webs and base flanges of the rails, and devices tending to constantly force the said wedges tightly against the chair and the plates. 125

2. The combination with the adjacent ends of railway rails; of a chair in which the abutting ends and the base flanges of the 130

rails are disposed, the said chair including oppositely disposed vertical brace members, a clamp plate fitted between each of the said brace members and the web of the opposing 5 rail ends, means engaging the said brace members and the said plates that constantly apply pressure to hold the said clamp members against the web and the base portion of the said abutting rail ends, 10 the said means consisting of wedges that engage the clamp plates, bearings on the brace members with which the wedges engage, the said bearings being vertically inclined with respect to the rails, whereby, 15 when the wedges are forced home, pressure is exerted on the clamp plates to cause them to tightly engage the webs and base flanges of the rails, and devices tending to constantly force the said wedges tightly against 20 the chair and the plates, said devices comprising telescopic rod members for each pair of wedges and coil springs disposed upon the rod members with their opposite ends engaging the opposing rod members, 25 whereby to normally expand the said rod members, the end of each rod member having engagement with the inner end of its respective wedge. 3. The combination with the adjacent ends 30 of railway rails; of a chair in which the abutting ends and the base flanges of the rails are disposed, the said chair including oppositely disposed vertical brace members, a clamp plate fitted between each of the said 35 brace members and the web of the opposing rail ends, means engaging the said brace members and the said plates that constantly apply pressure to hold the said clamp members against the web and the base portion of 40 the said abutting rail ends, the said means consisting of wedges that engage the clamp plates, bearings on the brace members with which the wedges engage, the said bearings being vertically inclined with respect to the 45 rails, whereby, when the wedges are forced home, pressure is exerted on the clamp plates to cause them to tightly engage the webs and base flanges of the rails, and devices tending to constantly force the said wedges

tightly against the chair and the plates, 50 said devices comprising telescopic rod members for each pair of wedges and coil springs disposed upon the rod members with their opposite ends engaging the opposing rod members, whereby to normally expand the said rod members, the end of each rod member having engagement with the inner end of its respective wedge, the brace members of the chair having tapered housings 55 for receiving the wedges, the clamp plates having projections provided with bearings with which the wedges engage, the housings having apertures through which the said projections on the clamp plates pass.

4. In a rail joint, a rail clamping chair 60 adapted to receive and secure the abutting ends of the rail sections, the said chair including oppositely disposed parallel side brace members, each of the said brace members having a horizontally extended housing 65 at each end, the back bearing of which is downwardly and outwardly inclined, said housing being also tapered inwardly from the inner to the outer end, the said brace members each having an aperture on that 70 side opposite the back bearings, a clamp plate having a foot portion, one of the said plates being fitted between each of the rail chair side members and the webs of the opposing rail sections, each of the said plates having a bearing web at each end that pass through the apertures at their respective 75 ends of the chair side members, said bearing webs each having a bearing face inclined in a plane parallel with the incline of the back bearing of the housing into which they project, a wedge block movable in each of the housings between the oppositely disposed inclined bearing faces of the 80 housing and the clamp plates, and means engaging the inner ends of each opposing pair of wedge blocks that automatically move the wedge blocks to their wedging position, as the rails and the parts of the 85 chair loosen under wear or contract under low temperature.

HANS P. JOHNSON.
